CLAIM

The ornamental design for the sign for aiding firefighters to locate children, as shown and described.

DESCRIPTION

FIG. 1 is a front elevational view of the sign for aiding firefighters to locate children showing my new design; FIG. 2 is a rear elevational view thereof; FIG. 3 is a left side elevational view thereof; FIG. 4 is a right side elevational view thereof; FIG. 5 is a top plan view thereof; and, FIG. 6 is a bottom plan view thereof. The broken line lettering in FIGS. 1 and 2 is for illustrative purposes only and forms no part of the claimed design.

FIG. 1

FIG. 2

FIG. 3

FIG. 4

FIG. 5

FIG. 6
